UNITED STATES PATENT OFFICE.

JOHN D. BRUNTON AND FRANK H. J. TRIER, OF WESTMINSTER, COUNTY OF MIDDLESEX, ENGLAND.

MACHINERY FOR DRESSING STONE.

SPECIFICATION forming part of Letters Patent No. 252,725, dated January 24, 1882.

Application filed September 28, 1881. (No model.)

To all whom it may concern:

Be it known that we, JOHN DICKINSON BRUNTON and FRANK HENRY JULIUS TRIER, (commonly known as FRANK TRIER,) subjects 5 of the Queen of Great Britain, and residing at 19 Great George Street, Westminster, in the county of Middlesex and Kingdom of England, have invented certain Improvements in Machinery or Apparatus for Dressing Stone, of 10 which the following is a specification.

Our invention relates to an arrangement whereby an arrising-tool, such as is described in the specification to former Letters Patent granted to us for the United States of America, 15 dated the 11th February, 1879, No. 212,182, may be applied to produce arrises upon stones dressed in a top-dressing machine of the construction described in the specification to our application for Letters Patent of even date 20 herewith, the arris-tool being attached to the cross-slide of such machine.

Figure 1 is a side elevation of part of a top-dressing machine, showing one of the standards, the cross-slide, and arris-tool, with the 25 mode of attachment to the cross-slide. Fig. 2 is a sectional elevation taken at right angles to Fig. 1. Fig. 3 is a plan of the same; and Figs. 4, 5, 6, 7, and 8, details hereinafter referred to.

30 A is the standard of the machine. B is the cross-slide. C is a suspending-bracket bolted to the back of B. D D' are tool-holders carried upon C by V-slides a a, permitting both D and D' to move along C from side to side of 35 the machine. E E are circular revolving cutters fixed on spindles b, and free to revolve with their spindles by contact of the cutters with the stone to be dressed. F F' are cutter-sockets carrying the cutter-spindles b b. FF' 40 are pivoted in D D' upon trunnions G, Figs. 4 and 5, and, together with the bush j, to be hereinafter described, are held in place by the nuts and washers c d. H H' are screws by which the tool-holders are moved from side to side of 45 the machine and are adjusted to the varying widths of stone to be operated upon. H is turned by the hand-wheel L only. H' is driven automatically in either direction by means of the fast and loose pulleys e and bevel-gear f

and g. The object of this difference in the 50 mode of moving the two cutter-holders is this: In order to produce arrises lengthwise of the bed or table of the machine, one or both cutters are fixed in the right position, as shown at E E, Fig. 2, and the stone fixed on the table is caused to move to and fro beneath them; but in producing an arris on a stone at right angles to the length of the table or across the machine the stone is stationary, and the cutter attached to the tool-holder D' is automatically 55 caused to move to and fro by the screw H', the cutter being in the position E', Fig. 1, D meanwhile being brought out of the way and as close to the hand-wheel as possible.

As described in the specification to our said 60 former Letters Patent No. 212,182, the cutter-socket is left free to turn upon the trunnion G for the purpose of taking a position slightly askew to the line of movement of the stone or of the holder. The amount of skew is determined by the width of the notch, in Fig. 6, in the collar of the cutter-socket, and the rotation on the trunnion is checked by the tube i, which is screwed into the face of the bush j. (See Figs. 5, 6, 7.) Through the tube i is 65 passed a pin, k, having a collar, l, on the end of which, after it is put in place in the tube, is screwed the eye m. Between l and the bottom of the tube i is a spiral spring, the function of which is to keep the end of the pin k up in the 70 holes n n n, which are made in the face of D. j is free to move round in D, and by withdrawing k until its end is free of D, j can be moved round and again fixed by permitting k to enter into any one of the holes n n. When the stone 75 comes into contact with the cutter it causes the socket F to move round to the extent permitted, and thus to give to the cutter the required skew.

In Fig. 1, E shows the position of a cutter 80 when arrising lengthwise of the machine, and E' the position when arrising across the machine.

In Fig. 2, E E show the cutters fixed to arris 85 the opposite edges of a stone lengthwise of the machine. An inclination of one in twenty-four is given to the cutters, as shown in Fig. 4, to give back clearance and to facilitate their cutting ac-

tion. This inclination should be given in the socket F' in one direction, as in Fig. 4, and in F in the other direction, as indicated by the dotted line o p.

5 Fig. 8 is an enlarged plan of part of D', showing mode of fixing the nut in which the screw H' works.

We claim as our invention—

10 1. The combination, with a top-dressing machine, of arris-tools mounted in pivoted adjustable sockets adapted to be set so as to produce arrises either lengthwise or crosswise of the bed or table, and arranged and operated substantially as hereinbefore set forth.

15 2. The combination, substantially as hereinbefore set forth, of the tool-holder, the arris-cutter, the pivoted adjustable socket for the same, adapted to be set so as to cause the tool to cut lengthwise or crosswise of the stone, and mechanism for reciprocating the tool-holder crosswise of the stone.

20 3. The combination of the tool-holders D D',

the arris-tools mounted and arranged in the tool-holders in the manner substantially as herein described, the cross-shafts H H', the means for actuating the same, and the bracket on which said tool-holders are supported and move, substantially as hereinbefore set forth.

In testimony whereof we have signed our names to this specification in the presence of two subscribing witnesses.
